UNITED STATES PATENT OFFICE.

CHARLES C. T. WILLSON, OF ALTCONA, PENNSYLVANIA.

DROP-DOOR RIGGING FOR HOPPER-CARS.

1,095,443.

Specification of Letters Patent.

Patented May 5, 1914.

Application filed July 11, 1913. Serial No. 778,581.

To all whom it may concern:

Be it known that I, CHARLES C. T. WILLSON, a citizen of the United States, residing at Altoona, in the county of Blair, State of Pennsylvania, have invented certain new and useful Improvements in Drop-Door Rigging for Hopper-Cars; and I do hereby declare the following to be a full, clear, and exact description of the invention, such as 10 will enable others skilled in the art to which it appertains to make and use the same.

This invention relates to drop door rigging for hopper cars.

The object of the invention resides in the 15 provision of a drop door rigging for hopper cars through the instrumentality of which the hopper doors may be opened and closed with facility.

A further object of the invention resides 20 in the provision of a drop door rigging whereby the doors on opposite sides of the car may be operated independently of each other, and in which the action of the rigging will be smooth and without any tendency to 25 buckle.

A still further object of the invention resides in the provision of a drop door rigging which will be simple in construction, efficient, positive in operation and durable.

With the above and other objects in view 30 the invention consists in the details of construction and in the arrangement and combination of parts to be hereinafter more fully described and particularly pointed out 35 in the appended claims.

In describing the invention in detail reference will be had to the accompanying drawings wherein like characters of reference denote corresponding parts in the several views, and in which—

Figure 1 is a side elevation of a double hopper car partly in elevation and partly in section and showing the improved rigging associated therewith; Fig. 2, an enlarged 45 side elevation of a fragment of what is shown in Fig. 1; Fig. 3, a view similar to Fig. 2 with the drop doors in open position; Fig. 4, a section on the line 4—4 of Fig. 2; Fig. 5, a section on the line through the operating shaft of the rigging; Fig. 6, a section on the line 6—6 of Fig. 4; Fig. 7, a section on the line 7—7 of Fig. 2; Fig. 8, a section on the line 8—8 of Fig. 7; Fig. 9, a side elevation of one of the chutes employed 50 in the rigging and showing the pivoted

chute bottom in elevated position in full lines and in lowered position in dotted lines, and Fig. 10, a section on the line 10—10 of Fig. 5.

Referring to the drawings A indicates a 60 double hopper car which includes front and rear hopper sections of corresponding construction and as the drop door rigging employed in connection with one hopper section is identical with the drop door rigging 65 employed with the other hopper section only the rigging associated with the one hopper section will be described in detail, the reference characters employed in connection therewith being applied to corresponding 70 parts of the drop door rigging associated with the other hopper section of the car.

Referring particularly to the hopper section of the car A the bottom of the car including said hopper section is shown as comprising angular portions 15 and 16. The angular portion 15 is provided with discharge openings 17 in its lower end, said openings being disposed on opposite sides of the longitudinal axis of the car A. Likewise the angular portion 16 is provided at its lower end with a pair of discharge openings 18 disposed respectively in alignment with the discharge opening 17 in the angular portion 15. The discharge openings 17 are 85 adapted to be opened and closed through the instrumentality of hinged doors 19, while the discharge openings 18 are adapted to be opened and closed by hinged doors 20.

Depending from the angular portion 15 90 in position to receive material delivered through the discharge openings 17 are chutes B having an open outer side and a hinged bottom 21 normally held elevated by fastening devices 22 and adapted to rest upon 95 respective rails 23 when the free ends of said bottoms are lowered.

Depending from the angular portion 16 in position to receive material delivered from the discharge openings 18 are chutes C 100 which also have open outer sides and include hinged bottoms 24 respectively normally held elevated by suitable fastening devices 25 and adapted to rest upon respective rails 23 when the free ends of the bottoms are 105 lowered.

Connecting the chutes B and C on the same side of the car A are inner and outer beams 27 and 28 and secured against the outer sides of the chutes B and C on the 110

same side of the car A are plates 29 of substantially inverted U-shape.

Secured against the outer side of each plate 29 is a plate 30 and secured to the sides of the car A above the plates 30 respectively are plates 31 provided respectively with arcuate slots 32.

Depending from the beams 27 and 28 are alined journaled bearings 33 in which are 10 rotatably mounted respectively extended hubs 49' of ratchet wheels 49. Engaged through the extended hubs 49' and through the ratchet wheel 49 are the squared outer ends 34' and 35' of sections 34 and 35 respectively of a shaft D. Detachably engaged on the squared outer ends 34' and 35' respectively are throwing arms 38 each provided at one end with an arcuate slot 39 and the remaining portion of said throwing arm 20 being provided with a plurality of openings 40 adapted to selectively receive the squared outer ends 34' and 35' respectively to vary the throw of the arms 38 during rotation of the shaft sections 34 and 35. Slidably en- 25 gaged in the slots 39 of the arms 38 respectively are corresponding ends of links 41, the outer ends of the links 41 carrying brackets 42 respectively. Pivotally connected to each bracket 42 are ends of links 43 and 44, which 30 latter are pivotally connected at their outer ends to brackets 45 and 46 mounted on respective doors 19 and 20 disposed on the same side of the car A, said links extending through openings 47 and 48 respectively 35 formed in the adjacent walls of the chutes B and C. The inner end of the section 34 is provided with a squared extension 36, while the inner end of the section 35 is provided with a squared recess 37 adapted to receive 40 the squared extension 36 whereby the shaft sections 34 and 35 may be locked together for simultaneous rotation. It will be noted that the connections between the throwing arms 38 and the links 41 are sufficiently loose 45 to permit requisite longitudinal movement of the sections 34 and 35 to position the extension 36 in and out of the recess 37, whereby the sections 34 and 35 of the shaft D may be connected and disconnected at will. 50 Each ratchet wheel 49 is provided with a plurality of teeth 50 limited by flanges 51 and 52 and one tooth 53 limited only by the flange 52 and extending through the flange 51 for a purpose that will presently appear. 55 Pivotally mounted on each plate 30 is a pawl 54 having a curved upper edge 55, said pawl being adapted for coöperation with the teeth 50 and 53 of the adjacent ratchet wheel 49 to lock the shaft sections 34 and 35 against rotation in one direction. Pivoted on each plate 30 is a lever 56 having a cam shaped lower end 57 adapted for coöperation with the curved edge 55 of the pawl 54, said coöperation being such that 60 65 when the lever 56 is rocked in one direction

the pawl 54 will be moved into engagement with the ratchet wheel 49, while the opposite movement of the lever 56 will move the pawl 54 out of engagement with the adjacent ratchet wheel 49. The end of each lever 56 remote from the pawl 54 is provided with a lateral stud 58 movable in the slot 32 of the adjacent plate 31 which construction serves to guide the lever 56 and limits the movement thereof. Each lever 56 is provided with a notch 59 which is adapted to be engaged by a pawl 60 pivoted on the plate 31, the engagement between said pawl 60 and notch 59 being effected when the pawl 54 is in engagement with the adjacent ratchet wheel 49 whereby the lever 56 is locked against movement that would effect the release of said pawl 54 from engagement with the adjacent ratchet wheel 49.

Assuming the parts to be in the position shown in Fig. 2 if it is desired to discharge the contents on both sides of the car A it is only necessary to disengage the pawls 60 from the levers 56 on each side of the car and then move said levers to the position shown in Fig. 3 which will disengage the pawls 54 from respective ratchet wheels 49. The outer end of either shaft section 34 or 35 is then engaged with a suitable tool such as a detachable crank and said shaft sections 95 rotated in unison toward the left in Fig. 2. This rotation of the shaft sections 34 and 35 will swing the arms 38 to the position shown in Fig. 3 when the upper ends of the links 41 will move in the slot 39 under the influence of gravity. The downward movement of the links 41 as a result of the movements of the arms 38 will draw the doors 19 and 20 toward each other through the medium of the links 43 and 44 so that material can 100 pass from the interior of the car through the openings 17 and 18 into respective chutes B and C from whence it will be discharged upon the ground or into any suitable conveyer.

If it is desired to discharge material from one side of the car only it is only necessary to disengage the shaft sections 34 and 35 by relative longitudinal movement there being sufficient play between the various connected parts to permit this movement of the shaft sections. It will be noted in this connection that when the parts are in the position shown in Fig. 2 the pawls 54 are engaged with the tooth 53 of the adjacent ratchet wheel 49 so 110 that the flange 51 of said ratchet wheel will not interfere with the longitudinal movement of the desired shaft section.

What is claimed is:—

1. In a hopper car the combination of a plurality of doors for controlling respective discharge openings of the car, individual mechanism for effecting the movement of said doors respectively to open and closed positions, and means for simultaneously op-

erating said individual mechanisms whereby said doors will be simultaneously moved to open and closed positions.

2. In a hopper car, the combination of a pair of doors disposed on each side of the longitudinal axis of the car for controlling respective discharge openings of the car, individual mechanisms for effecting the movement of each pair of doors disposed on the same side of the longitudinal axis of the car to opened and closed positions, and means for simultaneously operating said individual mechanisms whereby said pairs of doors will be moved simultaneously to opened and closed positions.

3. In a hopper car, the combination of a pair of doors disposed on each side of the longitudinal axis of the car for controlling respective discharge openings of the car, a

shaft journaled transversely of the car and including a pair of detachably interlocked sections adapted to be disengaged from each other by longitudinal movement of one section relative to the other, connections between said sections and respective pairs of doors for effecting the movement of the doors to open and closed position by the rotation of the shaft sections, and means for locking each of said shaft sections against rotation in one direction to maintain the doors of each pair in closed position.

In testimony whereof, I affix my signature, in the presence of two witnesses.

CHARLES C. T. WILLSON.
